UNITED STATES PATENT OFFICE.

OLIVER H. SMITH, OF WASHINGTON, DISTRICT OF COLUMBIA, ASSIGNOR TO MARVIN A. CUSTIS, OF WASHINGTON, DISTRICT OF COLUMBIA.

FASTENING DEVICE FOR MAIL-BOXES.

No. 918,385.

Specification of Letters Patent.

Patented April 13, 1909.

Application filed May 2, 1908. Serial No. 430,603.

To all whom it may concern:

Be it known that I, OLIVER H. SMITH, a citizen of the United States, residing at Washington, District of Columbia, have invented certain new and useful Improvements in Fastening Devices for Mail-Boxes, of which the following is a specification.

This invention relates to that class of fastenings designed for securely locking in position upon a post, building, or other support, such receptacles, boxes, or casings as are usually exposed out of doors and utilized for various purposes, and which are only intended to be capable of being opened by an authorized person.

While capable of the general application above indicated, the invention possesses special utility as a fastening device for mail boxes, and has particularly in view a simple, easily locked, and practical fastening of this character which enables a mail box to be securely and effectually locked to its post or other support, and positively prevents the box from being removed in any way except by manipulation from the inside of the box by an authorized person with a key to the box. Therefore, the present invention is intended to secure a mail box against removal by unauthorized agencies by means of a fastening device only operable from the inside of the box, and which is also secure against being "picked" from the outside of the box.

A further object of the invention is to provide an improved fastening device of the character noted, which is thoroughly housed from weather conditions, involves but few parts and an entire absence of springs or other complications, and which is also readily adaptable to the standard letter box fittings which are now largely employed in the U. S. postal service.

With these and many other objects in view, which will more readily appear as the nature of the invention is better understood, the same consists in the novel construction, combination, and arrangement of parts herein-after more fully described, illustrated and claimed.

The essential features of the invention, involved in the relationship between the catch and locking members of the device, are necessarily susceptible to structural modifications, and to embodiment in different forms of construction, without departing from the

scope of the invention, but certain practical embodiments thereof are suggested in the accompanying drawings, in which:

Figure 1 is a face view of the coupling piece of the main supporting elements for the box, 60 exposing one form of the improved fastening device seated in said coupling piece. Fig. 2 is a similar view of the holder bracket of the main supporting elements which is usually bolted or otherwise permanently secured to 65 the post or other support. Fig. 3 is a longitudinal sectional view of the complete device, showing the same in its locked condition. Fig. 4 is a view similar to Fig. 3, illustrating the catch member tilted back to its inoperative position, permitting the letter box to be removed from its support. Fig. 5 is a cross sectional view on the line 5—5 of Fig. 4. Figs. 6 and 7 are details in perspective, 75 respectively of the tiltable catch member and of the locking member or guard employed in the construction shown in Figs. 1, 3 and 4. Fig. 8 is a sectional view similar to Fig. 3 showing a preferable form of the invention involving a tiltable catch member which is so pivoted to the coupling piece of the main support. Figs. 9 and 10 are views similar to Figs. 6 and 7, respectively of the catch member and the locking member embodied in the construction shown in Fig. 8. Fig. 11 is a 85 detail view of an expedient that may be resorted to to provide for holding the locking guard against movement when in its locking position with reference to the catch member.

Like references designate corresponding 90 parts in the several figures of the drawings.

It is the purpose of the present invention to preserve, as far as possible, the standard letter box fittings such as generally employed in the U. S. postal service, and to equip these 95 fittings with the improved fastening device claimed herein, though it will of course be understood that the fastening device can be used with any suitable supporting elements which provide for coupling the box to a post 100 or other support. However, for illustrative purposes, the standard letter box fittings are shown in the drawings, and the same primarily comprise the slidably interlocked elements 1 and 2 which are respectively secured permanently by bolts, screws, or other fasteners, to the post or other support 3, and to the back wall of a mail box 4. The element 1 constitutes what may be termed a holder bracket of a general hollow dovetailed form— 105 110

tion and formed with the inclined or curved longitudinal side retaining flanges 5, and at its lower end with a forwardly projecting shield flange 6. According to the present invention, it is proposed to also provide the holder bracket 1, at a suitable point therein, with a forwardly projecting and horizontally disposed keeper projection or abutment 7, the purpose of which will be presently explained. The said other element 2 constitutes a coupling piece of a hollow dovetailed formation, having the inclined or curved side engaging flanges 8 slidably embracing and interlocked with the flanges 5 of the bracket 1. Also, the coupling piece 2 is provided at the top with a rearwardly projecting shield flange 9 adapted to cover and close in the top of the holder bracket 1, while the bottom flange 6 of the latter performs a corresponding function for the bottom of the coupling piece 2. Furthermore, the said coupling piece 2 is preferably provided near its bottom edge, with an offset guard projection or flange 10 which overlaps the bottom shield flange 6 and hence protects the device against the insertion of a "pick" by an unauthorized person with burlarious intent.

To provide for adapting the improved locking device to the fittings above described, the base plate portion 11 of the coupling piece 2 is provided therein with a receiving opening 12 within which are seated the two members 13 and 14 constituting the fastening device which cooperates with the keeper projection 7. The member 13 is a tiltable catch member, and referring first to the construction shown in Figs. 1 to 7, inclusive, it will be observed that this catch member essentially consists of a bar arranged longitudinally within the opening 12 and provided with an overbalanced weighted upper end 15, and formed at its lower end with what may be termed rest elements or feet 16 having a loose support at the bottom edge of the opening 12. At one side the catch member is provided with oppositely arranged offstanding rounded cam projections 17 and the said catch member is further provided with a longitudinal guiding and housing recess or slot 18 extending practically the full length of the bar forming the catch member and communicating at the top with a keeper groove 19. The said recess 18 slidably houses therein the locking member 14 which constitutes a shiftable locking guard. This locking guard is preferably made of a single bar or strip of metal and is provided at its upper end with a laterally deflected lock projection 20 which is preferably inclined or curved to have a wedging engagement with a correspondingly curved beveled cam face 21 at the engaging end of the catch member. At its lower end, the locking guard 14 is provided with a forwardly projecting finger piece 22 projecting through a play opening

23 in the mail box wall, and at an intermediate point, the said locking guard 14 is provided with a presser element 24 whose end portions are in the form of wedge elements 25 having a wedge engagement with the cam projection 17 of the catch member 13.

The parts described may be conveniently, and loosely, held within the opening 12 by a transverse retainer bar 26 secured to the coupling piece 2 and bridging the opening 12 at one side of the members 13 and 14.

From the foregoing it will be observed that in applying the mail box to its support, the coupling piece 2 is slid onto the bracket 1, with the locking guard 14 elevated so that its presser 24 lies over the cam projection 17 and holds retracted the weighted upper engaging end 15 of the catch member. In this position the lock projection 20 engages upon the top edge of the catch member so that when the parts reach the position shown in Fig. 4, it is simply necessary to draw the guard 14 downward to release it from the cam projection 17, and thus permit the overbalanced weighted end 15 to move into locking engagement beneath the fixed keeper projection 7. Then by inserting in the play opening 23 a temporary stop block or equivalent element 26^a, the locking guard is held against movement so that the fastening device could not be released by turning the post or support upside down and thus reversing the parts.

With the construction described, when it is desired to release the fastening, it is simply necessary for the party who has access to the box to release the finger piece 22 and then slide the guard 14 upwardly, which moves the wedges of the presser 24 over the cam projection 17 and thereby retracts the engaging end 15 of the catch member to the cleared position shown in Fig. 4.

In the preferable and simplified form of the invention shown in Figs. 8, 9 and 10, the presser and cam elements herein described, are omitted, and instead of having simply a loose mounting of the catch member 13, the latter is provided at an intermediate point, and at opposite sides with pivot studs 27 having a pivotal mounting in bearings provided therefor at the sides of the receiving opening 12 in the coupling piece 2. Also, in this construction, the wedge action provided for by the elements 20-21 is unnecessary, as when the parts are brought together with the finger holding the locking guard 14 elevated, it is simply necessary to release the finger from the finger piece 22 when the coupling piece 2 has dropped to its lowest position, whereupon the engaging end of the catch member will move under the keeper projection 7 and the locking guard will drop down bringing its projection 20 at one side of the engaging end of the member 13 with the result of holding such end locked against any possibility

of becoming disengaged from beneath the keeper 7 except through the authorized raising of the locking guard to clear the projection 20 from the top of the catch member. 5 After thus clearing the projection 20, in the construction shown in Fig. 8, it is also necessary to press laterally upon the finger piece end of the guard 14 to draw back the engaging end of the catch member so that the mail 10 box can be lifted off of its support.

In carrying out the invention, various expedients may be utilized to insure the best and most practical results, and in this connection it may be observed that though the 15 tiltable catch member is shown as provided with an overbalanced weighted upper end, it will, of course, be understood that the feature of causing the upper end of the catch member to move beneath and into engagement with the keeper projection 7 may be effected in various ways, such as the wedging action shown in Fig. 4, or by equivalent means without departing from the scope of the invention. Also, instead of employing a 20 temporary stop block 26^a for holding the locking guard against movement from its locking position, any equivalent means may be substituted, such for instance as suggested in Fig. 11 of the drawings. In this 25 figure of the drawings, there is illustrated the idea of providing the lower end of the locking guard with a hinged and shouldered finger piece 22^a adapted to be swung into engagement with an edge of the opening 23 and thereby provide an effectual holding stop 30 which secures the locking guard against movement until the said hinged finger piece has been released from the inside of the box.

Various other changes in the form, proportion, and minor details of construction may 40 be resorted to without departing from the spirit or sacrificing any of the advantages of the invention.

I claim:

45 1. A fastening device of the class described comprising a fixed supporting element having a keeper, a removable coupling member, a catch member carried by the coupling member and engaging the keeper, and a shiftable guard having a locking engagement with the catch member.

2. A fastening device of the class described comprising a fixed element having a keeper, a coupling element, a catch member carried 55 with the coupling member and having an overbalanced end engaging the keeper, and a locking guard for locking said catch member.

3. A fastening device of the class described 60 comprising a fixed member, a removable element, a catch member carried with the removable element and having a locking engagement with said fixed member, and a locking guard having a locking engagement 65 with said catch member.

4. A fastening device of the class described comprising a fixed element, a coupling element, a catch member carried with the coupling element and having a weighted end having a locking engagement with the fixed 70 element, and a locking guard shiftably mounted at one side of the catch member and having means for locking the latter.

5. A fastening device of the class described, comprising a fixed element having a keeper, 75 a coupling element, a catch member carried with the coupling element and having an overbalanced end engaging the keeper, and a locking guard slidably mounted at one side of the catch member and having at one end 80 a lock projection to engage behind the engaging end of the catch member, and at its other end having a finger piece exposed from the inside of the box to which the fastening is applied.

85 6. A fastening device of the class described comprising a fixed element, a coupling element, a pivotal catch member carried with the coupling element and having a locking engagement with said fixed element, and a locking guard having a locking engagement with the catch member.

90 7. A fastening device of the class described, comprising a fixed element having a keeper, a coupling element, a tiltable catch member 95 carried with the coupling element and having a pivotal mounting therein at an intermediate point between its ends, said catch member having a weighted engaging end and a guiding and housing recess, and a locking 100 guard slidably mounted in said recess and provided at one end with a lock projection to engage behind one end of the catch member, and at its other end having a finger piece exposed from the inside of the box to 105 which the fastening is applied.

8. In a device of the class described, the 110 slidably interlocked supporting elements, one of which elements carries a shield flange at the top thereof, and the other of which supporting elements carries a shield flange at the bottom thereof, one of said supporting elements also carrying as an additional member a supplemental guard projection arranged to bridge the joint or space at the 115 free edge of said bottom shield projection, and fastening means housed within said two elements.

9. A fastening device of the class described, 120 comprising a fixed member having a keeper, a removable member, a catch member carried by said removable member, a locking guard having a locking engagement with the catch member, and a stop for holding said locking guard against movement.

125 10. A fastening device of the class described, comprising a fixed member having a keeper, a removable member, a catch member carried by said removable member, a locking guard for the catch member, and a 130

stop consisting of a hinged element at one end of the locking guard and arranged to engage a fixed element for holding the locking guard against movement.

5 11. In a device of the class described, the slidably interlocked supporting elements and fastening means housed within said elements, one of said elements being provided at the top with an overhanging shield flange,
10 and one of said elements being provided at

the bottom with an offset guard projection so arranged as to close one end of the space between the two elements against the insertion of a picking tool or similar instrument.

In testimony whereof I hereunto affix my 15
signature in the presence of two witnesses.

OLIVER H. SMITH.
